CURVED CONDUIT

Frank R. Higley, Cleveland Heights, Ohio

Application December 16, 1931, Serial No. 581,342

6 Claims. (Cl. 137—112)

This invention relates to improvements in the type of conduit having a curved way, that is, to a device having a through passageway, the entrance to which is adapted to receive flow from one direction; the conduit being adapted to change the direction of this flow, so that the conduit discharge opening, at the opposite end of the way, will discharge the flow in another direction. A typical example is the ordinary elbow pipe fitting adapted to interconnect a pair of straight pipe lengths angularly related but in a common plane.

A consideration of such a pipe fitting will make evident that, in its normal functioning, the path of a unit of volume, in the stream through the curve of the system will be entirely dependent upon where such unit enters the curved fitting. If the unit enters at the outside of the bend it will travel through the fitting along the outside of the curvature of the latter. But if the unit enters at the inside of the bend, if the velocity of flow be sufficiently low, such unit will travel along the inside of the bend; and its path through the conduit will consequently be much shorter than that of the unit first considered. If the velocity and mass of the second considered unit be sufficiently high, it will tend to maintain its original direction of motion and pass across the conduit on a line beginning at the inside of the bend but ending at the outside of the bend. In either event it will be apparent that flow through the fitting will be accompanied by considerable relative motion between the units of volume in the stream, producing a turbulence which materially impairs the efficiency of operation.

It is the object of my invention to eliminate such turbulence. Briefly, I accomplish this by providing means whereby in the stream, all units with reference to the sectional area transverse to the flow, will have paths of equal length through the curve.

More specifically, to this end, I provide, in a conduit having a curved way of substantially uniform sectional area, means in said way for causing the absolute path of flow of a unit of volume in the stream along said way, to be helical, with such angular advancement about the mean path of said way, as said mean path extends along the curve of said way, that the absolute paths of all units of volume are substantially equal.

The invention has particular application where large masses are to be handled, as in turbine draft tubes; where high velocities are met, as in steam lines and the air inlet passages of internal combustion engines; and where the nature of the materials to be handled makes the handling diffi-

cult, such as in devices for feeding coal or other solids in pieces.

The exact nature of this invention together with further objects and advantages thereof will be apparent from the following description taken in connection with the accompanying drawing, wherein two applications of the invention are conventionally illustrated, Figs. 1-4 inclusive illustrating the invention as applied to a 90° or elbow bend and Figs. 5-7 illustrating the invention as applied to a 180° or return bend. More specifically, Fig. 1 is a view in section, of a conduit showing (in elevation) partition means therein, and in broken lines arrows indicating paths of flow therethrough; Figs. 2 and 3 are opposite end views of the complete conduit indicated in Fig. 1; Fig. 4 is a transverse section as in the plane of line 4—4, Fig. 1; Fig. 5 is a view similar to Fig. 1 but of a conduit having a way of 180° curvature; Fig. 6 is an end view of the same, and Fig. 7 is a section as in the plane of line 7—7, Fig. 5.

With reference now to Figs. 1-4 of the drawing, 1 is a conduit having a curved way of circular sectional area, the curvature of said way being on an arc of 90°. Thus, in the position of Fig. 1, the conduit has a horizontal inlet direction and a vertical outlet direction.

Within said way I arrange a partition member 2 extending diametrically across the way in every section thereof transverse to the general path therethrough, and extending along the way throughout the latter. Also, the partition member 2 has a twist as indicated in the drawing, such that its transverse direction at the discharge end of the conduit is disposed 180° from that at the entrance thereto, with reference to the curved center line of the way.

Thus the general curved way through the conduit is actually divided into two passages, A and B, one on either side of the partition 2. These passages are also curved. They are in fact arranged helically in twisted relation, with 180° of angular advancement about the mean path of the way as said mean path extends along the curve of the way. Thus the inlet end of the passage A is at the outside of the curve of the conduit but the discharge end of the passage A is at the inside of the curve of the conduit. Likewise, the inlet end of the passage B is at the inside of the curve of the conduit but the discharge end of the passage B is at the outside of the curve of the conduit. Consequently flow through the conduit will be as indicated by the arrows a—a and b—b, Fig. 1.

With reference now to Figs. 5-7, the conduit

1a is similar to the conduit 1 except that it has 180° of extent. In other words, its way is curved in a half circle so that the conduit has parallel entrance and discharge directions. The partition 5 2a is likewise similarly diametrically disposed, with a twist, as is the partition 2. The total twist of the partition 2a is still 180°, so that the amount of twist per unit of advancement along the mean path of travel is only 1/2 that of 10 the partition 2. Still the curved way of the conduit is divided into a pair of passages C and D arranged helically in twisted relation, with 180° of angular advancement about the mean path of the way as said mean path extends along the 15 curve of the way; and consequently the actual paths of flow through the conduit will be as indicated by the arrows Fig. 5, the arrow c—c indicating the path of flow through the one passage C and the arrow d—d indicating that 20 through the passage D.

The employment of the partition means 2 shown, is not essential to my invention. The result of equalizing paths of flow as described, could be accomplished by equivalent structure 25 such as by otherwise deforming the section of the curved way through the conduit. Although desirable, it is not essential that the partition means 2 be diametrically disposed as described nor indeed is it necessary that only a single partition means be employed. Thus any plurality of helically disposed inwardly extending ribs might serve the purpose, or the conduit might merely be deformed as to present a flattened or square section, the section twisting as it advances. Nor is it essential, although desirable, 35 that the partition 2 at its ends lie as illustrated, in planes transverse to that of the curvature of the conduit, provided the total twist of the partition or its equivalent deformation be 180°. 40 In the embodiments illustrated in the drawing, the conduit itself might conceivably be of cast metal and the partition 2 of relatively thin sheet metal, secured as by welding. Obviously, however, the parts might be integral and of any 45 other suitable material.

The twist, or rate of angular advancement of the partition means 2 or its equivalent, is in the

ordinary application preferably not uniform along the length of the curve. Instead it desirably increases from zero at each end to a maximum amount intermediate the ends; so that in straight pipe lengths which may lead to and from the curved conduit section, flow will be in straight lines without twist, and the least energy will be absorbed in passing around the bend. 80

What I claim is:

1. In a conduit having a curved way of the class described, helical guide means in said way for causing the absolute path of flow of a unit of volume of a stream moving along said way to be helical with substantially 180° of angular advancement, about the mean path of said way as said mean path extends along the curve of said way. 85

2. In a conduit having a curved way, helical guide partition means in said way arranged to impart a half revolution of motion about the mean path of flow, to flow generally along the curve of said way. 90

3. In a conduit providing a curved way, helical guide means deforming said way into a plurality of passages arranged helically in twisted relation, with 180° of angular advancement about the mean path of said way as said mean path extends along the curve of said way. 100

4. In a conduit having a curved way, diametrical guide partition means therein having a twist of 180° along the curve of said way. 105

5. In a conduit having a curved way of the class described, helical guide vane means disposed to cause the absolute path of flow of a unit of volume of a stream moving along said way to be helical with substantially 180° of angular advancement, about the mean path of said way as said mean path extends along the curve of said way. 110

6. In a conduit having a curved way of the class described, helical guide means for causing the absolute path of flow of a unit of volume of a stream moving along said way to be helical with substantially 180° of angular advancement, about the mean path of said way as said mean path extends along the curve of said way. 115
